UNITED STATES PATENT OFFICE.

JOSEPH M. SALADINER, OF BRYAN, TEXAS.

GATHERING ATTACHMENT FOR BOLL-WEEVIL EXTERMINATORS.

Application filed May 5, 1922. Serial No. 558,740.

To all whom it may concern:

Be it known that I, JOSEPH M. SALADINER, a citizen of the United States, residing at Bryan, in the county of Brazos and State of 5 Texas, have invented a new and useful Gathering Attachment for Boll-Weevil Exterminators, of which the following is a specification.

This invention relates to gathering means 10 for use in connection with boll weevil exterminators of the type shown, for example, in Patent No. 1,354,215 issued to me on Sept. 28, 1920.

It is an object of the invention to provide 15 flexible trailing means adapted to be drawn over the surface of the ground between the rows of plants, these trailing means being in communication with a suction mechanism whereby perforated squares, hulls, and boll 20 weevils or other insects on the ground will be gathered up into the machine and crushed.

A further object is to provide means for separating dirt and sand from the material sucked into the machine, additional means 25 being employed for removing the sucked material from the air current and directing it to a crushing mechanism.

With the forgoing and other objects in view which will appear as the description 30 proceeds, the invention resides in the combination and arrangement of parts and in the details of construction hereinafter described and claimed, it being understood that, within the scope of what is claimed, 35 changes in the precise embodiment of the invention shown can be made without departing from the spirit of the invention.

In the accompanying drawings the preferred form of the invention has been shown.

40 In said drawings

Figure 1 is a side elevation of a boll weevil exterminator having the present improvements combined therewith.

Figure 2 is a view partly in elevation and 45 partly in section of one of the gathering members, some of the fingers being removed.

Figure 3 is an enlarged longitudinal section through one of the connecting pipes and showing the dirt trap thereunder.

50 Figure 4 is a longitudinal section through the separator.

Figure 5 is a section through the grinding mill supplied from the separator.

Figure 6 is a plan view of the machine.

55 Figure 7 is a view partly in section and partly in elevation of a group of gathering

fingers and showing the articulated interior structure.

Figure 8 is a transverse section through one of the flexible hose.

Referring to the figures by characters of reference 1 designates supporting wheels having an axle 2 carrying a body 3. To the rear portion of this body is hingedly connected the frame 4 of a hood 5 extending transversely across the back of the machine. This hood is made up of oppositely disposed sections mounted to swing about transverse axes and operated by cables 6 or the like extending to suitably located controlling 70 levers 7 and guided by sheaves 8 provided wherever necessary. The construction of the hood and the means for swinging the hood upwardly by means of the levers and cables constitutes in itself no part of the 75 present invention. It might be stated, however, that each side section of the hood has a collecting pipe 9 extending along the back portion thereof and rearwardly along the outer side. To the rear portion of each of these pipes is connected a flexible hose 10 provided, at its lower end, with a coupling 11 provided with several branches from each of which is extended a flexible tubular finger 12 closed at its free end. Each finger 85 has a longitudinal series of inlet openings 13 and the hose 10 and fingers 12 are so proportioned and located that when the machine is drawn forward with the hood extending over several rows of plants, the fingers 12 will be caused to drag over the ground between and close to the rows so that practically every part of the surface of the ground between the rows will at some 90 time be subjected to the action of suction 95 as hereinafter pointed out.

A suction fan is adapted to rotate within a casing 14 suitably located on the body 3 and this casing is provided at its side with intake pipes 15 connected, as at 16, to the 100 outlet 17 of a separator 18. The outlet is intersected by a screen 19 and opening into the separator at a point directly opposite the outlet 17 is a branched pipe or coupling 20 connected by flexible hose 21 or the like to 105 the side portions of the respective pipes 9.

The casing of the separator 18 is preferably substantially cylindrical and has an outlet 22 in the bottom thereof from which extends a delivery chute 23. A shaft 24 is 110 journaled in the separator casing and has radial blades 25 adapted to move between

the outlet 17 and the inlet pipe or coupling 20.

A gear 26 is secured to shaft 24 and receives motion through a gear 27 from a shaft 5 having a pulley 29 driven by a belt 30. This belt is mounted on a pulley 31 which rotates with another pulley 32 journaled on a crank arm 33 carried by the casing 14. Pulley 32 normally rests by gravity on a 10 belt 34 which serves to drive a pulley 35 on the shaft 36 of the suction fan located in casing 14.

Belt 34 is driven by a pulley 37 mounted on a shaft 38 and this shaft, in turn, has 15 sprockets 39 at its ends which receive motion through chains 40 from larger sprockets 41 secured to and rotating with the supporting wheels 1. Clutches 38' controlled by levers 39' can be provided for coupling the 20 sprockets 39 to or uncoupling them from the shaft 38.

Formed within the bottom portion of each of the flexible hose 10 is a longitudinal series 25 of outlet openings 42 and secured to each of these hose is a receptacle 43 having an outlet opening 44 which is normally closed by a door 45 of any suitable construction. These receptacles are adapted to receive sand or other heavy material drawn upwardly into 30 the hose 10 and which will gravitate through the openings 42.

An additional receptacle 46 is secured to the bottom portion of and extends longitudinally of each of the rearwardly extending 35 side portions of the pipes 9. Each receptacle 46 has an outlet in the bottom thereof as shown at 47 and a closure 48 of any desired construction serves to hold the contents from escaping through the outlet. 40 Openings 49 are provided in the bottom of each of the pipes and serve to deliver sand and other heavy material to the receptacle 46.

Mounted on the body 3 is a mill shown in detail in Figure 5 and which includes a 45 housing 50 the top of which has a tapered recess 51 the lower open end of which is flared as at 52 to provide a grinding surface. The chute 23 opens into the upper portion of the recess 51 so as to deliver material thereto. A shaft 53 is journaled in the housing 50 and within a frame 54 secured to and extending under the open bottom of the housing. To the upper portion of this 50 shaft is secured a tapered spiral feeding element 55 and below this feeding element is arranged a grinding disk 56 adapted to cooperate with the grinding surface of the flared end 52 so as to reduce to a finely comminuted state all material delivered to 55 the mill. A spring 57 bears upwardly against the disk 56 so as to press it yielding- 60 ly against the housing. A gear 58 is secured to shaft 53 and receives motion through a gear 59 from a shaft 60 provided with a sprocket 61. This sprocket is engaged by

a chain 62 which is driven by a sprocket 63 formed with or secured to another sprocket 64 which engages and is driven by the chain 40.

From the foregoing it will be apparent 70 that when the machine is drawn forward motion will be transmitted to the various working parts of the apparatus from the sprocket 41 and the parts driven thereby. A suction will be set up through the hose 10 and fingers 12, the air current passing through the separator shown in Figure 4 and out through the screen 19 to the fan casing. As the fingers 12 trail over the surface of the ground the suction will cause 80 loose particles and organisms such as perforated squares, hulls, insects, etc., to be sucked into the openings 13 and thence through the hose 10. Any sand or other heavy particles being carried by the air currents will gravitate through the openings 85 42 into the containers 43. As the air currents pass over the openings 47 any remaining heavy particles will gravitate into the receptacles or containers 46. The air currents will merge in the pipe or coupling 20 and flow straight across the separated casing to the outlet 17. The screen will prevent the squares, etc., from passing out through the outlet and the rotating blades of the separator will throw these squares and other solid portions downwardly to the outlet 22.

As they are here out of the line of suction 90 they will gravitate through the chute 23 to the mill where they will be reduced by the rotation of the feed spiral or worm 55 and disk 56. The pulverized material can be discharged directly on the ground.

In the drawings there have been shown 95 some structures which do not constitute any part of the present invention. For example a poison containing hopper has been indicated at 65 and from this hopper are extended tubes 66 for delivering poison through the hood 5. This poison distributing means 100 has already been described and claimed in my patent heretofore mentioned.

It is to be understood that the fingers 12 can be of any construction desired. As illustrated in Figure 7 each finger can consist of a flexible tube 67 closed at its free end and having its other end provided with a rigid sleeve 68 having a flange 69 riveted or otherwise secured to a flange 70 on the branch of the coupling 11. Arranged within each tubular portion 67 can be an articulated reenforcement consisting of a series of links 71 pivotally connected to each other and each being substantially basket shaped with an opening 72 in the bottom thereof adapted to register with one of the openings in the tubular portion 67. Particles sucked through the openings in the tubular portion 67 and the open bottoms 72 will flow longitudinally through the links and toward the 110 120 125 130

coupling 11 as will be obvious. The links in the free end portion of the tubular member 67 can be shaped so as to fit snugly within said end of the member, as shown at 73 5 while the link at the other end of the articulated reenforcement is adapted to be riveted or otherwise fastened to the sleeve 68, as shown at 74.

As shown in the drawings the flexible hose 10 in the apparatus can, if desired, be stiffened by providing longitudinal ribs 75 on the inner surfaces of the hose.

What is claimed is:—

1. The combination with a portable structure, of means for creating a suction, flexible hose in communication with said means, diverging tubular fingers carried by and communicating with each of said hose, said fingers having inlet openings, and adapted 20 to trail on the surface of the ground, receptacles beneath and supported by the hose, there being openings in the hose for delivering particles from the hose to the receptacles.
- 25 2. The combination with a portable structure and suction means thereon, of a collecting pipe in communication with the suction means and having outlets in the bottom portion thereof, a receptacle connected to the pipe for receiving material gravitating through the outlets, flexible hose extending from the collecting pipe and having openings in the bottom portions thereof, receptacles carried by the hose for receiving particles gravitating through the openings, and 30 apertured fingers opening into the hose.
- 35 3. The combination with a portable structure and suction means thereon, of a flexible hose in communication with said means and

having outlet openings in the bottom portion thereof, a receptacle fitted to the hose and movable therewith for receiving particles gravitating through the openings, a branched coupling carried by the hose, and diverging apertured tubular fingers carried 45 by the branches of the coupling.

4. The combination with a flexible hose and a coupling connected thereto, of a flexible finger attached to the coupling and comprising a tubular portion closed at its free 50 end and having a plurality of openings between its ends, a series of links extending longitudinally within said tubular portion, said links being pivotally connected and constituting means for holding the tubular 55 portion extended, each link having an opening therein communicating with one of the openings in the tubular portion of the finger, said links providing a continuous passage therethrough longitudinally of the finger.

5. A suction finger comprising a tubular portion closed at one end and open at its outer end and having a plurality of openings between its ends, pivotally connected 65 basket shaped links fitted snugly within the tubular portion for holding it distended, each of said links having an opening registering with one of the openings in the tubular portion.

In testimony that I claim the foregoing as my own, I have hereto affixed my signature in the presence of witnesses.

JOSEPH M. SALADINER.
